UNITED STATES PATENT OFFICE.

PAUL SCHLOSSMANN, OF PHILADELPHIA, PENNSYLVANIA.

APPARATUS FOR FINISHING KNIT FABRICS.

SPECIFICATION forming part of Letters Patent No. 595,893, dated December 21, 1897.

Application filed December 5, 1896. Serial No. 614,566. (No model.)

To all whom it may concern:

Be it known that I, PAUL SCHLOSSMANN, a citizen of the United States, residing at the city of Philadelphia, in the county of Philadelphia and State of Pennsylvania, have invented certain new and useful Improvements in Apparatus for Finishing Knit Fabrics, of which the following is a specification.

My invention has relation to apparatus for the finishing of knit fabrics, particularly such fabrics or goods which are of coarse or rough material, and in such connection it relates to an apparatus whereby the fabric is subjected to attrition between two flat carriers, which carriers are subjected to pressure by passing the same through pressure or feed rollers.

Heretofore knit fabrics—such as stockings, underwear, and the like—have first been formed into desired shape by stretching the same over flat boards or forms and either drying the fabric thereon or pressing the fabric on the board by placing the board and fabric in a steam-press. Should the fabric thus treated not receive the required luster or finish, it is removed from the boards and laid between immovable flat surfaces and subjected to pressure with or without heat. This method of finishing has been largely unsatisfactory, and particularly so when applied to fabrics knit from coarse or cheap material.

The principal objects of my present invention are, first, to provide an apparatus whereby a high finish may be given to knit fabrics irrespective of their quality or texture and without the application of heat thereto; second, to provide an apparatus for finishing knit fabrics which consists in subjecting the fabric to attrition between two flat carriers during the passage of said carriers through pressure or feed rolls and without the application of heat to said fabric, and, third, to provide an apparatus for the finishing of knit fabrics which consists, essentially, of two flat boards or carriers between which the fabric is placed and a series of two or more pressure or feed rolls between which the boards or carriers are caused to travel.

My invention, stated in general terms, consists of an apparatus for finishing knit fabrics, substantially as hereinafter described and claimed.

The nature and scope of my invention will

be more fully understood from the following description, taken in connection with the accompanying drawings, forming part hereof, 55 in which—

Figures 1, 2, and 3 represent, diagrammatically and in section, the apparatus for carrying out my invention of finishing knit fabrics embodying main features of my invention and 60 illustrating, respectively, the relative positions assumed by the carriers and fabric as the carriers pass through the pressure or feed rolls.

Referring to the drawings, *a* and *a'* represent 65 two rolls, which may be either pressure or feed rolls.

b and *b'* represent two flat boards or carriers adapted to travel between the rolls *a* and *a'*, and *C* represents the fabric placed between the boards or carriers *b* and *b'* and adapted to be finished thereby during the passage of said carriers between said rolls *a* and *a'*, as hereinafter more fully explained.

In carrying out my invention of finishing 75 knit fabrics the fabric *C* is first placed between the flat boards *b* and *b'*, which boards may be of pasteboard, wood, or any other suitable material, glazed or unglazed. The ends of the boards *b* and *b'* are then inserted 80 between the rolls *a* and *a'*, as indicated in Fig. 1, the meshes of the fabric at that end of the boards being thereby compressed, while the boards *b* and *b'* assume an angular position with respect to each other. The boards 85 and fabric are then fed through the rolls until they next assume the position shown in Fig. 2, wherein the meshes of the fabric are compressed and lie between the boards *b* and *b'*, which have assumed a substantially parallel 90 position with respect to each other. As the boards and fabric leave the rolls, as indicated in Fig. 3, the last end of the fabric is compressed and the boards assume an angular position with respect to each other, which position is opposite to the initial angular position of the boards, as shown in Fig. 1. The 95 action of the boards or carriers upon the fabric *C* as the boards assume the various positions illustrated in the drawings is as follows:

The successive portions of the fabric are first compressed and are then permitted to expand to their original form or shape. This compression and expansion of the fabric rubs 100

or abrades the meshes against the boards, and thus the fabric takes on a high polish or luster, which may be increased, if desired, by passing the boards and fabric again between the rolls *a* and *a'* or between two similar rolls located in advance of said rolls *a* and *a'*. The rolls *a* and *a'* and boards *b* and *b'* need not be heated, and in practice I have found that heating the rolls or carriers does not increase or lessen the finish or luster on the fabric caused, as above described, by the attrition of the meshes of the fabric upon the boards or carriers.

Having thus described the nature and objects of my invention, what I claim as new, and desire to secure by Letters Patent, is—

An apparatus for finishing knit fabrics, com-

prising two non-yielding carriers wholly independent of each other between which the fabric is placed, and two feed-rollers between 20 which said carriers are wholly supported and impelled to assume successively converging parallel and diverging positions with respect to each other and the fabric to cause the faces of said fabric to be subjected to attrition to finish the same, as described. 25

In testimony whereof I have hereunto set my signature in the presence of two subscribing witnesses.

PAUL SCHLOSSMANN.
